United States Patent Office

Des. 181,433
Patented Nov. 12, 1957

181,433

ACOUSTIC TILE

Eve Murray, Hollywood, Calif., assignor to
K. G. Bierlich, Hollywood, Calif.

Application February 23, 1956, Serial No. 40,269

Term of patent 3½ years

(Cl. D18—2)

The figure is a top perspective view of an acoustic tile, showing my new design.

I claim:

The ornamental design for an acoustic tile, substantially as shown.

References Cited in the file of this patent

UNITED STATES PATENTS

D. 140,784 Vogelman _____ Apr. 10, 1945